DESIGN FOR AN ADHESIVE TAPE DISPENSER

Benjamin Bronfman, Lynbrook, N. Y., assignor to
The Cofax Corporation, a corporation of New York

Application July 27, 1946, Serial No. 132,020

Term of patent 14 years

(Cl. D74—1)

To all whom it may concern:

Be it known that I, Benjamin Bronfman, a citizen of the United States of America and resident of Lynbrook, county of Nassau, and State of New York, have invented a new, original, and ornamental Design for an Adhesive Tape Dispenser, of which the following is a specification, reference being had to the accompanying drawing, forming a part thereof, in which

Fig. 1 is a perspective view from the right of an adhesive tape dispenser embodying my design.

Fig. 2 is a top plan view of the dispenser, shown in Fig. 1, and

Fig. 3 is an end elevational view thereof.

I claim:

The ornamental design for an adhesive tape dispenser, as shown.

BENJAMIN BRONFMAN.
